CLAIM

The ornamental design for a handset for a medical infusion pump, as shown and described.

DESCRIPTION

The file of this patent application contains at least one drawing/photograph executed in color. Copies of this patent or patent application with color drawings(s)/photograph(s) will be provided by the Office upon request and payment of the necessary fee.

FIG. 1 is a top perspective view of a handset for a medical infusion pump showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a rear, top, and left side perspective view thereof;

FIG. 9 is a front, top, and left side perspective view thereof;

FIG. 10 is a front, top, and right side perspective view thereof;

FIG. 11 is a rear, top, and right side perspective view thereof;

FIG. 12 is a rear, bottom, and left side perspective view thereof;

FIG. 13 is a front, bottom, and left side perspective view thereof;

FIG. 14 is a front, bottom, and right side perspective view thereof; and,

FIG. 15 is a rear, bottom, and right side perspective view thereof.

(Continued)

The broken lines in FIG. 7 depict portions of the handset for a medical infusion pump that form no part of the claimed design.
